Primary Examiner — Manpreet S Matharu*Assistant Examiner* — Suzanne E Tisdell(74) *Attorney, Agent, or Firm* — Marshall, Gerstein & Borun LLP(57) **CLAIM**

The ornamental design for a energy storage unit, as shown and described.

DESCRIPTION

FIG. 1 is a front, left-side perspective view showing our new ornamental design.

FIG. 2 is a front view thereof;

FIG. 3 is a left-side view thereof;

FIG. 4 is a right-side view thereof;

FIG. 5 is a back view thereof;

FIG. 6 is a top view thereof; and,

FIG. 7 is a bottom view thereof.

The broken lines in the drawings illustrate boundaries and/or environmental structures of the energy storage unit that form no part of the claimed design.

1 Claim, 5 Drawing Sheets(56)
